UNITED STATES PATENT OFFICE.

CASPER FAUST, OF OSHKOSH, WISCONSIN.

SAFETY-GATE FOR BRIDGES.

1,015,880.

Specification of Letters Patent.

Patented Jan. 30, 1912.

Application filed May 12, 1911. Serial No. 626,671.

To all whom it may concern:

Be it known that I, CASPER FAUST, a citizen of the United States, and resident of Oshkosh, in the county of Winnebago and State of Wisconsin, have invented certain new and useful Improvements in Safety-Gates for Bridges; and I do hereby declare that the following is a full, clear, and exact description thereof.

10 The primary object of my invention is to provide a simple and effective safety gate attachment for swinging bridges such as shown in a patent issued to me November 1st, 1910, No. 974,558, specific objects being 15 to provide a weight-power mechanism in connection with an actuating gear, all being disposed under the bridge abutment whereby the gates are closed when the bridge is opened; to provide curved cam-rails in connection with a bridge-actuating gear whereby the gates are opened incidental to the bridge being closed; to provide a spring-controlled tappet roller for engagement with the curved cam-rails whereby shock incidental to engagement thereof is eliminated; to provide anti-friction hangers having cam-rails and their connections, and also to provide a spring connection between the gates and their pivot posts to permit a limited 25 yield of the gates incidental to shock caused by accidental contact therewith when they are closed or partially closed.

With the above objects in view the invention consists in certain peculiarities of construction and combination of parts as hereinafter set forth with reference to the accompanying drawings and subsequently claimed.

40 In the drawings Figure 1 represents an inverted plan view of a portion of one end of a swinging bridge and its abutment having attached thereto safety gate mechanism embodying the features of my invention; Fig. 2, a longitudinal sectional view of the apparatus, the section being indicated by line 2-2 of Fig. 1; Fig. 3, a detail cross-section of the abutment, the section being indicated by line 3-3 of Fig. 1, said view illustrating the gates in their closed position; 45 Fig. 4, a detail cross-section of the plunger-rod and its anti-friction bearing-block, the section being indicated by line 4-4 of Fig. 1; Fig. 5, a detail sectional view of a cam-rail and its link connection with a bridge abutment, and Fig. 6, a detail sectional view

of a yielding spring hanger connection between the gate and its pivot-post.

Referring by characters to the drawings 1 represents the end of a swinging bridge and 2 the abutment, the bridge being shown in its closed position in Figs. 1 and 2. Secured to the bridge 1 is a roller tappet 3 which tappet is mounted in the forked end of a stem 3', the stem being reciprocatively mounted in a bracket 3'', which bracket, in turn, is secured to a block that projects from the lower face of the bridge. The forward end of the stem 3' is provided with a pin 4 that is engaged by one end of a coiled spring 4' which coiled spring surrounds the stem 70 with its opposite end abutting an ear of the bracket 3'', the coiled spring serving to hold the tappet roller in its forward position. The tappet-roller is arranged to engage the curved faces of oppositely disposed cam-rails 5, 5, which cam-rails have their outer ends connected to the abutment by links 6, the same being mounted in ears of the cam-rails and ears 7 of brackets, which are, in turn, secured to a cross-timber A of the 80 bridge abutment. The inner ends of the cam-rails are in hinge connection with each other, the pintle-bolt of the hinge connection being also passed through ears of a plunger-bar 8 whereby said cam-rails are 85 supported at their joint.

The forward end of the plunger-bar is guided between anti-friction rollers 9 and a bottom roller 10, all of which rollers are mounted in a bracket 10' that is also secured 90 to the abutment cross-timber. The rear end of the plunger-bar is provided with a toothed rack-section 8' which is in meshed engagement with a pinion 11, the bar being guided at this end by an L-shaped strap 12 95 which is secured to an abutment cross-timber B. Movement of the plunger-rod in either direction is limited by lugs 12', 12'', that extend therefrom and are adapted to engage opposite faces of the strap 12. The plunger-bar is normally held forward in the position indicated by dotted lines in Fig. 1 by a weight 13, which weight is suspended from a cable 13' that passes over a pulley 14, the latter being mounted in a hanger 14' that 105 is secured to the abutment. The opposite end of the cable is connected to a lug 13'' that extends from the plunger-bar and when the bridge is swung to its open position causing the tappet roller to travel free of the 110

cam-tracks, the said weight will thus draw the plunger-bar forward, which movement will cause a pair of gates C, C', to swing across the abutment and close the approach to said bridge. This movement is effected through movement of a crank-pin 15 that extends from an arm 16, which arm is connected to the pinion 11 through an arbor 17, which arbor is rotatably mounted in the abutment cross-timber B, the pinion and crank-pin being thus secured to constitute a single member.

While I have shown the arbor as being fast to the pinion, it is obvious that the same 15 may be fixed and that the crank-pin 15 and its arm 16, together with the pinion may be arranged to rotate upon the arbor, in which instance the latter would be fixed.

Alined with the axis of the pinion upon 20 opposite sides thereof are pivot-posts 18, which posts are suitably journaled in the abutment and extend therethrough for the purpose of supporting the gates C and C'. Each pivot-post has secured to its lower end 25 a crank-arm 19, the crank-arm of one pivot-post set parallel with the crank-pin arm 16 of the pinion 11, the other crank-arm being set upon the opposite side of an imaginary line intersecting the axes of the pinion and 30 pivot-posts. Each crank-arm 19 is connected to the crank-pin 15 by a pitman 20, the pitmen being formed in two sections that are connected by turn-buckles 21 whereby they may be adjusted as to length.

35 The gates C, C' are secured to their pivot-posts 18 by leaf-spring connections 22, whereby a slight yield of the gate is permitted independent of any movement of said pivot-post. This yield is desirable 40 when the gates are subjected to sudden shock when closed in order that the parts may not be broken or otherwise injured. The pivot-posts are also provided with toothed gear-wheels 23 which are meshed 45 with similar gear-wheels 23', the latter being secured to pivot-posts 24 which carry sidewalk gates 25. The gear-wheels are suitably inclosed in housings 26 that have standards 27 extending therefrom, which 50 standards terminate with apertured ears for the reception of the upper ends of the pivot-posts 18 and 24. By this arrangement when the road gates are swung to their closed position the gear connection between the 55 sidewalk gates will cause the same to swing in the opposite direction and thus effectually cut off the approach to the bridge, the sidewalk and road gates being arranged to fold backward when the bridge is closed, as indicated by dotted lines in Fig. 1.

60 From the foregoing description it will be seen that when the bridge is swung to its closed position from either direction, the tappet roller will engage either one of the 65 curved cam-tracks 5 and after a slight yield

due to the spring connection of said tappet the cam-tracks will be forced backwardly to the position shown in Fig. 1, in opposition to the weight-controlled plunger-bar 13. When the cam-tracks are forced backward 70 it will be observed that their ends which are in link connection with the abutment will have a slight movement, which movement is taken up by said links. Incidental to backward thrust of the plunger-bar 75 the gear connection comprising the rack and pinion will cause a rotation of the latter, which rotation, in turn, will be imparted to the pivot-post whereby the road-gates and sidewalk gates will be folded back to 80 permit free access to the bridge. When the bridge is swung to its open position the weight 13 will cause the gates to swing across the roadway and sidewalk to the position indicated and in swinging to this position 85 it will be observed that the crank-pin 15 will move across the center of an imaginary line intersecting the axes of the pinion and ends of the crank-arms whereby the pitmen will automatically lock in such position that the gates cannot be forcibly 90 opened from above until such time as their gear connection under the abutment is operated through closure of the bridge. Particular attention is also called to the anti-friction forward bearing of the plunger-rod 95 whereby its weight and side thrust incidental to movement imparted thereto will not cause any binding and thus the entire mechanism will move with the least possible 100 friction.

I claim:

1. In a swinging bridge having a tappet adjacent to its end, and an abutment with which the bridge is adapted to register; the combination of a reciprocative rack-carrying weight-controlled plunger-bar mounted beneath the abutment, a single pinion in meshed engagement with the plunger-bar, a crank-arm carried by the pinion, opposite pivot-posts journaled in the abutment, a gate secured to each post above the abutment, a crank-arm secured to the lower end of each pivot-post, to extend upon opposite sides of a line intersecting the axes of the pinion and pivot-posts, the crank-arm of which pinion is disposed parallel to that of one of the pivot-post crank-arms, pitmen connecting said pivot-post crank-arms and the pinion crank-arm, cam-rails having 110 their outer ends fulcrumed to the abutment, their inner ends being in hinge connection with the plunger-bar arranged to be engaged by the tappet whereby the plunger-bar is actuated in opposition to its weight-control to open the gates incidental to 115 swinging of the bridge to its closed position.

2. A swinging bridge comprising a spring-controlled tappet disposed adjacent to its end, an abutment with which the 120

bridge is adapted to register, a reciprocat-
5 tive rack-carrying plunger, a weight in
cable connection with the plunger whereby
the same is moved in one direction, a single
pinion in meshed engagement with the rack
portion of the plunger, a crank-arm carried
10 by the pinion, oppositely disposed pivot-posts journaled in the abutment, a gate in yielding connection with each post,
15 a crank-arm secured to the lower end of
each pivot-post, the crank-arms being ex-
tended upon opposite sides of a line inter-
secting the pinion and pivot-post axes, the
crank-arm of the aforesaid pinion being dis-
20 posed parallel to one of the pivot-post
crank-arms, pitmen connecting said pivot-
post crank-arms and the pinion crank-arm,
cam-rails having their inner ends in hinge
connection with the plunger-bar, links con-
25 necting the outer ends of the cam-rails and
abutment, the rails being arranged in the
path of travel of the tappet whereby move-
ment of the plunger-rod is effected in op-
position to its weight-control to cause the
gates to swing open.

3. In a swinging bridge having a tappet
disposed adjacent to its end, an abutment
with which the bridge is adapted to regis-

ter, and swinging gates carried by the abut-
ment; the combination of a single pinion in 30
link connection with the gates, a plunger-bar
provided with a rack section for engage-
ment with the pinion, a rear guide for the
plunger-bar, a bracket through which the
forward end of the plunger-bar extends, 35
side rollers carried by the bracket for en-
gagement with the plunger-bar, a bottom
roller carried by the bracket upon which
said plunger-bar is adapted to travel, curved
40 rails having their inner ends in hinge con-
nection with the plunger-bar, their outer
ends being in link connection with the abut-
ment, the rails being arranged in the path
of travel of the bridge tappet whereby the
45 plunger is operated in one direction to
open the gates, and a weight connected to
the plunger, whereby the latter is operated
in the opposite direction to close the gates.

In testimony that I claim the foregoing
I have hereunto set my hand at Milwaukee 50
in the county of Milwaukee and State of
Wisconsin in the presence of two witnesses.

CASPER FAUST.
